DESIGN FOR A PAN OR SIMILAR ARTICLE

Philip E. Willman, Chicago, Ill.

Original application March 24, 1933, Serial No. 47,566, now Design Patent 90,609, dated August 29, 1933. Divided and this application June 9, 1933. Serial No. 48,359. Term of patent 7 years

To all whom it may concern:

Be it known that I, PHILIP E. WILLMAN, a citizen of the United States, residing at Chicago, in the county of Cook and State of Illinois, have invented a new, original, and ornamental Design for a Pan or Similar Article, of which the following is a specification, reference being had to the accompanying drawing, forming part thereof.

Figure 1 is a view in side elevation of the article showing my new design; and

Figure 2 is a top plan view of the article shown in Figure 1.

This application is a division of the application filed March 24, 1933, by the present applicant, bearing Serial No. D-47,566, (now Design Patent 90,609, issued Aug. 29, 1933).

I claim:

The ornamental design for a pan or similar article, substantially as shown.

PHILIP E. WILLMAN.
